UNITED STATES PATENT OFFICE.

ARANT J. KRAMER, OF PITTSBURGH, PENNSYLVANIA.

SHOCK-ABSORBER.

1,396,851.

Specification of Letters Patent.

Patented Nov. 15, 1921.

Application filed December 16, 1920. Serial No. 431,240.

To all whom it may concern:

Be it known that I, ARANT J. KRAMER, a citizen of the United States, residing at Pittsburgh, in the county of Allegheny and State of Pennsylvania, have invented certain new and useful Improvements in Shock-Absorbers, of which the following is a specification.

This invention relates to shock absorbers for motor vehicles for neutralizing or minimizing the effects of shocks and jars thereto, and resist the throw of the car body under the influence of road inequalities.

Objects of the device are to provide a shock absorber of the character described, in a manner as hereinafter set forth, which will operate to resist abnormal throw of the car body, under adverse road conditions, without liability of breaking the spring or racking the car, and which permits of lateral movement of the car body without cramping or binding the working parts of the absorbing device.

Further objects of the invention are to provide a device of the class stated which is simple in its construction and arrangement, strong, durable and efficient in its use, readily installed, attractive in appearance, positive in its action, and comparatively inexpensive to manufacture.

To the accomplishment of these and such other objects as may hereinafter appear, the invention consists of the novel construction, combination and arrangement of parts herein specifically described and illustrated in the accompanying drawing, wherein is shown an embodiment of the invention, but it is to be understood that the device shown is merely illustrative of what is now thought to be the best embodiment thereof and that various changes in the form, proportion, and minor details of construction may be resorted to, without departing from the principle or sacrificing any of the advantages of the invention, which come within the scope of the claims hereunto appended.

In the drawing forming a portion of this specification and wherein like numerals of reference designate corresponding parts throughout the several views:

Figure 1 is a side elevation of the shock absorber, in accordance with this invention,

mounted on the front axle with a portion of the latter broken away.

Fig. 2 is a top plan view of the sustaining lever.

Fig. 3 is a side elevation illustrating a slightly modified form of shock absorber mounted on the rear axle with portions of the latter broken away.

Fig. 4 is a sectional view of the rear axle perch and associated parts.

Referring to the drawing, the application of my improved device is illustrated in connection with the front and rear axles of a Ford automobile, but it will be understood that the same may be associated with any type of motor car, or for any purposes, wherein it is found applicable.

In the illustrated embodiment of the invention 1 indicates the front axle of an automobile, having mounted therein the usual spring perch 2. The angularly disposed apertured upper end 3, of the perch 2, instead of being positioned to extend inwardly, is positioned to extend outwardly toward the adjacent wheel, thereby eliminating the necessity of providing a special perch for use in connection with my improved shock absorber.

The sustaining lever 4, extending longitudinally with respect to the axle 1, comprises the body portion 5, a pair of inwardly projecting spaced arms 6, 7, and a pair of outwardly projecting and depending lugs, 8, 9. The lever 4 is pivotally connected to the perch 2, by means of the bolt 10 which passes through the apertures 11 in respective lugs 8, 9, and through the aperture in the upper end 3 of the perch 2 which is positioned between said lugs 8, 9. Ample clearance is provided between the lugs 8, 9, so as not to impede the vertical movement of the inner end of the lever during the operation of the device.

The under side of the body portion 5 of the lever 4, adjacent to the lugs, 8, 9, is formed with an aperture 12 by which the upper end of a link hanger 13 is pivotally connected by means of a bolt 14. The end 100 of the main automobile spring 15 is pivotally connected in the lower end of the hanger 13 by the bolt 16.

The arms 6, 7, of the lever 4, are formed

with the angularly disposed depending inner ends 17, 18, respectively, which straddle the spring 15 passing therebetween.

Fixed to the center of the axle 1, by means 5 of a spring clamp 19, is a leaf sustaining spring 20 having a yoke-shaped end 21 secured by a shackle 22. The yoke portion 21 forms a guide-way 23 for the travel of the roller 24, mounted therein and rotatably 10 carried by the bolt 25, which latter is fixed in the apertures 26 in respective inner ends 17, 18 of the lever 4.

The sustaining spring 20 may be comparatively light, owing to the length of the bifurcated inner end of the lever 4 and the connection of the vehicle spring 15, through 15 the link hanger 13, near the outer end of the said lever 4.

The yoke portion 21 of the sustaining spring 20 provides a compensating connection to permit of a variable movement of the roller 24 in the guide-way 23 during the functioning of the lever 4.

The action of the sustaining spring 20 not 25 only serves to neutralize the abnormal recoil of the vehicle spring 15, but normally acts to minimize the jolts and jars concomitant in the operation of the vehicle spring under ordinary conditions due to small in- 30 equalities of the road.

The modified form of the shock absorber, illustrated in Fig. 3 of the drawing, is identical in operation as that of the preferred form shown and described above, but differs 35 slightly in construction, owing to the difference in construction of the front and rear axles of the vehicle.

In the use of the device on the rear axle 40 of the vehicle, a special perch 27 is provided, which is bolted, as at 28, to the hub disk 29. The lever 30 is formed with a depending lug 31 which acts as an abutment to limit the outward movement of the link hanger 32, and in consequence the lateral 45 throw of the car body carried by the vehicle spring 33. The sustaining spring 34 functions identically to that described relative to the sustaining spring 20 of the preferred form.

50 Due to the position of the gear housing 35 on the rear axle 36 an independent sustaining spring is provided at each end of the axle and secured thereto by means of a spring clamp 37. In the preferred form the sustaining spring 20 is anchored at its center 55 by a clamp 19 to the center of the axle 1, thereby providing the sustaining element for both devices mounted on opposite ends of the axle.

60 What I claim is:

1. A shock absorber comprising an anchored resilient sustaining element having a yoke-shaped outer end, a sustaining lever having its outer end pivoted and further 65 having a depending inner end, a link piv-

otally connected at one end to the sustaining lever and adapted to have its other end attached to a vehicle spring, said link carried by the lever intermediate the ends of the latter, and means to provide a slidable connection between the depending inner end of the lever and the yoke-shaped outer end of the sustaining element. 70

2. A shock absorber comprising an anchored resilient sustaining element having a yoke-shaped outer end, a sustaining lever having its outer end pivoted and further 75 having a depending inner end adapted to straddle a vehicle spring, a link pivotally connected to said lever and adapted to be pivotally connected to the vehicle spring, and means to provide a slidable connection between the yoke-shaped outer end of the resilient element and the depending inner end of the lever below the vehicle spring. 80

85 3. A shock absorber comprising a sustaining lever adapted to be pivotally connected with a vehicle axle at its outer end and having a depending inner end provided with a bifurcated portion, a link pivotally attached to the lever and adapted to be pivotally connected to a vehicle spring forwardly of the inner end of the lever, a resilient sustaining element adapted to be attached with the axle, and a slidable connection 90 between the said element and the bifurcated portion straddling the vehicle spring. 95

4. A shock absorber comprising a sustaining lever adapted to be pivotally connected at its outer end with a vehicle axle and having a depending inner end, a link pivotally attached to the lever near the outer end of the latter and adapted to be pivotally connected to a vehicle spring, a resilient 100 sustaining element arranged below the vehicle spring and adapted to be attached with the axle, said element having a yoke-shaped end permanently connected to and slidably 105 engaging with the inner end of the lever. 110

5. A shock absorber comprising a sustaining lever including a body portion having a pair of outwardly extending lugs adapted to be pivotally connected with a vehicle axle, and further including a pair of inwardly 115 projecting spaced arms, a link pivotally connected to said body portion in proximity to said lugs and adapted to be pivotally connected to a vehicle spring extending between said arms, a resilient sustaining element adapted to be anchored to the vehicle 120 axle, and means arranged between said arms for slidably connecting one end of the sustaining element with said lever below said spring. 125

6. A shock absorber comprising a sustaining lever having its front formed with a pair of forwardly projecting lugs adapted to be pivotally connected with a vehicle axle, and its rear end formed with a pair of in- 130

wardly extending spaced arms, a link pivotally connected at its upper end to said lever in proximity to said lugs and adapted to have its lower end pivotally connected to the outer end of a vehicle spring, a resilient sustaining element adapted to be anchored on the vehicle axle and having its outer end

yoke shaped, and means arranged between said arms for slidably connecting the inner end of the sustaining lever to the yoke 10 shaped end of the sustaining element.

In testimony whereof I affix my signature.

ARANT J. KRABER.
